UNITED STATES PATENT OFFICE.

AUGUST B. RIPPE, OF SALT LAKE CITY, UTAH.

AWNING WINCH.

Application filed March 2, 1925. Serial No. 12,657.

To all whom it may concern:

Be it known that I, AUGUST B. RIPPE, a citizen of the United States, residing at Salt Lake City, in the county of Salt Lake 5 and State of Utah, have invented certain new and useful Improvements in Awning Winches, of which the following is a specification.

My invention relates to awning winches 10 and has for its object to provide a new and economical means of raising and lowering awnings and of automatically locking the same to hold an awning at any desired position.

15 In the use of awnings in front of stores and windows it has been the practice to use a worm wheel drive or a number of sets of bevel gears for raising and lowering said awnings. With my device I do away 20 with the use of the slow action of the worm gears and wheel and also use less bevel gears than has heretofore been the practice; I also provide means to automatically lock said device when the awning has been adjusted to the desired height.

These objects I accomplish with the device illustrated in the accompanying drawings in which similar letters and numerals of reference indicate like parts throughout 30 the several views and as described in the specification and pointed out in the appended claims.

In the drawings in which I have shown the best and most substantial embodiment 35 of my invention, Figure 1 is a side elevation of my device in connection with a lowered awning. Figure 2 is an elevation showing the awning raised and locked, and with the winch turning member removed. Figure 40 3 is an end view of my device with the crank and unlocking key removed. Figure 4 is a front view of the end of my crank rod and unlocking handle and Figure 5 is a side elevation of the same.

45 In the drawings I have shown the common awning A with its supporting rods B attached to the wall of a building. A bevel gear 1 is secured on a horizontal roller shaft C on which the body of the awning is wound. The teeth of said bevel gear 1 mesh with the teeth of a bevel pinion 2, which is secured on a vertical shaft 3, which shaft is mounted in a bearing bracket 4 that is firmly secured to the wall of the building. The said shaft C is journalled in bearings supported by the said bracket 4. The

lower end of the pinion shaft 3 is supported by a collar 5 that rests on another wall bracket 6. A catch 7 is slotted and pivoted to and around the said pinion shaft 3, and which catch is weighted or made heavier at one end than the other end, in order that the heavy end of said catch will normally assume a position lower than the lighter end as shown in Figure 3. On the lighter 60 end of said catch 7 a hook 8 is formed to engage said bracket 6 when the catch is in normal position. A U-shaped pin 9 is secured through the lower end portion of said pinion shaft 3 with the legs of said U-shaped pin bent upwardly and parallel with said shaft. A crank rod 10 is bifurcated at one end and each prong is bent to form a hook as shown at 11, and on the side of the rod opposed to the hook 11, a key plate 12 70 is attached.

The operation of my device is as follows: The prongs 11 of the crank rod 10 are engaged over the U-shaped pin 9 which is the means for joining the crank rod 10 with 80 the pinion shaft 3 and turning the pinion shaft 3. As the said hooks 11 are made to engage with the U-shaped pin 9 the key plate 12 will move the weighted end of the catch 7 upwardly to free the hook 8 from 85 its engagement with the horizontal portion of the bracket 6. The said pinion shaft 3 may then be rotated in either direction by rotating the crank rod 10 to raise or lower the awning by rolling or unrolling the 90 awning over the rod C. When the said crank rod 10 is disengaged from the pinion shaft 3 the hook 8 of the weighted catch 7 will engage the horizontal portion of the bracket 6 and lock the awning in the position desired.

Having thus described my invention I desire to secure by Letters Patent and claim:

1. An awning winch comprising, a set of bevel gears; bearing brackets for said gears; a pinion shaft having a U-shaped pin in one end thereof and said shaft secured to or connected with the pinion of said bevel gears; a pivoted locking member having one end heavier than the opposite end; a bracket for supporting said pinion shaft, and a crank rod bifurcated and curved at one end for engaging said U-shaped pin with a key plate for moving said locking member.
2. An awning winch comprising a bevel

gear secured on one end of an awning roller shaft; a bevel pinion whose teeth mesh with the teeth of said bevel gear; a vertical shaft on which said bevel pinion is secured; a bearing bracket in which the lower end of said pinion shaft is journalled; a U-shaped pin secured through the lower end portion of said pinion shaft with the legs of said pin extended upwardly; a weighted catch pivoted on said pinion shaft; a hook portion of said catch adapted to normally hold the shaft against rotation; a crank

rod having one end bifurcated and bent to form hooks to engage with the legs of said U-shaped pin; and a key plate attached to the bifurcated end of said crank rod adapted to move the heavy end portion of said catch upwardly and disengage said catch from its normal engagement with the pinion rod bracket. 15

20 In testimony whereof I have affixed my signature.

AUGUST B. RIPPE.
